PAGE 2

Fig. 2

Fig. 4

Fig. 5

Fig. 5

Fig. 7

Fig. 6

Fig. 1 is a top perspective view of a hydroplane, showing my new design;

Fig. 2 is a bottom perspective view thereof;

Fig. 3 is a side elevation thereof;

Fig. 4 and 5 are top and bottom plan views, respectively, of the hydroplane; and

Fig. 6 and 7 are front and rear elevations, respectively, thereof.

The dominant features of my design reside in the portion shown in full lines.

I claim:

The ornamental design for a hydroplane, as shown.
